UNITED STATES PATENT OFFICE.

OBERLIN SMITH, OF BRIDGETON, NEW JERSEY.

GARMENT-HANGER.

1,169,202.

Specification of Letters Patent. Patented Jan. 25, 1916.

Application filed March 31, 1914. Serial No. 828,525.

To all whom it may concern:

Be it known that I, OBERLIN SMITH, of Bridgeton, in the county of Cumberland, and in the State of New Jersey, have invented a certain new and useful Improvement in Garment-Hangers, and do hereby declare the following is a full, clear, and exact description thereof.

The object of my invention is to provide a hanger for garments of various kinds, especially coats, vests, trousers, ladies' sacks, shirt waists, etc., which will facilitate and render easy the application and removal of garments and which will conserve closet space, while withal being simple and inexpensive, and to this end my invention consists in the garment hanger constructed substantially as hereinafter specified and claimed.

20 In the accompanying drawings Figure 1 is a perspective view of one embodiment of my invention; Fig. 2 is a cross section through the same; Fig. 3 is a cross section on the line 3—3 of Fig. 2; Fig. 4 is a perspective view of another form of my invention; Fig. 5 is a cross section similar to Fig. 3 showing a different construction; Fig. 6 is a detail view in section of combined friction disks and spacing sleeve.

30 In carrying my invention into practice, I utilize any one of the various forms of garment hangers adapted to support such garments as coats, by suspending them upon curved arms, and such garments as trousers, skirts, or the like, by clamping or gripping them, but getting rid of certain annoying features growing out of the use of these devices due to the suspension thereof by means of hooks caught over brackets, or rods. As 35 ordinarily constructed and used, these devices so lack stability when they are suspended that it is very troublesome to apply a garment thereto, or remove it therefrom, and ordinarily the device must be lifted off 40 its rod or hook which makes the operation of removing or applying the garment awkward and inconvenient, because only one hand is fully available for the purpose.

45 By my invention the garment-engaging device itself, while conveniently having any of the ordinary forms as to the matter of the garment supporting portion, is so mounted or supported that it possesses such inherent stability during the operation of applying or removing a garment that both hands

are fully available for the purpose. Generally described, I pivotally mount the garment-engaging-member proper upon an arm that is pivotally mounted upon a fixed support within the clothes closet, or compartment, so that by swinging said arm forward into the forepart of the closet, being thereby separated from a group, or series of others (it being preferable ordinarily to have a group 60 or series thereof), so that it is presented in position for the convenient and comfortable application of the garment to, or its removal therefrom, while by its swinging it in the opposite direction the hanger is returned to 65 its inner or rear position, means being provided to hold, or secure it automatically in each of its two extreme positions.

Describing with some detail the embodiments of my invention which are shown in 70 the drawings, 10 designates the garment support proper suited for the hanging of coats, trousers, etc., each, instead of the customary hook for hanging, being provided with an eye 11 by which it is pivotally suspended 75 on the outer end of a light arm 12. The inner end of the arm 12 is enlarged and is rounded to form more or less of a disk 13, which is provided with a central hole for pivoting it upon a shaft 14. On each side 80 of the disk or head portion 13 there is a disk 15 that is mounted upon the pivoted shaft 14, means being provided to prevent turning 85 of the disks 15 upon the shaft and the latter also being nonrotatable, so that by the application of proper pressure from the disk 15 upon the arm head 13 enough friction may 90 be produced, which, while allowing the ready turning of the arm, when it is desired, will, nevertheless, securely hold it from 95 turning under the weight of any garment it may support. A convenient limit of swing 100 to the arm is 60 degrees to each side of a vertical plane through the axis, and as it is desirable to provide a positive stop to limit the swing of the arm this can readily be done by providing on the upper portion of each disk 15, a flange, or lip 16 that overhangs the periphery of the disk portion of the arm and provides at each end a shoulder 105 17, which the edge of the arm strikes when the limit of swing is reached.

While various devices by which to provide a pivotal support for the arms and a non-rotary support for the friction produced 110

disks 15 may be employed, an efficient and otherwise desirable construction is the one shown in the drawings wherein the shaft 14 takes the form of a tube that is provided 5 with a longitudinal slot 18 into which projects a key like lug 19 on each disk 15 so that thereby disks and shaft are held in nonrotative relation; and the support for the shaft 14 is effected by means of a rod 10 or bolt 20 which passes through the tubular shaft 14 and provision is made for securing it to, or mounting it upon supports in the clothes closet, or compartment. In the construction shown in Fig. 1, the rod 20 is 15 comparatively short, it being designed to support a small number of hangers and it requires a support for itself only at one end, which support may take the form of a flange, or collar, 21 that is attached to the 20 side wall of the closet, or to the usual shelf-supporting cleat, or ledge 22 thereof, several screws 23 being passed through holes near the periphery thereof and if desired the rod itself being prolonged either in the form 25 of a wood screw 24, or a threaded end adapted to pass through the wall and receive a clamping nut on the opposite side. The flange or collar 21 is provided with a key or spline 25 which enters the slot 18 in the 30 tubular shaft 14 and thereby the tubular shaft is securely restrained from rotation. the outer end of the rod 20 is threaded and upon it is placed a butterfly nut 26, which, through the medium of an interposed metal 35 washer 27 applies pressure to an elastic ring 28 which acting upon the outermost washer 15 of the end garment hanger applies a yielding pressure to the entire series of disks and arms mounted upon the tubular shaft 14. Adjacent garment hangers, or units are 40 spaced apart by short sleeves 29 placed over the tubular shaft 14 between the disks 15 of adjacent units. If desired a sleeve and its two adjacent disks may be of one piece, 45 in the form of a spool, as shown in Fig. 6.

In the form of my invention illustrated in Fig. 3, the supporting and tension producing rod 20 being of a length to carry a large number of garment hangers, or units, is 50 mounted in the outer ends of a pair of brackets 30 which are secured to the closet wall and in this case the bracket eye is provided with a key, such as the key 25 of Fig. 2, to hold the tubular shaft 14 from turning. 55 I thus show in the drawings two modes of support, but it is to be understood I do not limit myself to any particular means for mounting or supporting my garment hanger, or to supporting the same from any 60 particular portion of the closet or receptacle. Where a shelf is used it will be convenient to suspend the support from the under side of the shelf and in various ways the adaptations may vary.

65 I show in Fig. 5 another form of non-ro-

tative support than the slotted tube 14. In this case a rod or shaft 140 square in cross section, but with its corners slightly rounded, is employed, and the disks 15 are provided with square openings to conform to the 70 shape of the rods 140 in cross section while the arms 12 are provided with preferably round openings so the disks 15 cannot turn with the arms 12, but may turn as freely as friction of the disks upon them will permit. 75

The structural efficiency and simplicity of my invention will be evident when it is considered that a single, or common adjusting device provides the required friction for all of the swinging arms and yet each arm may 80 be swung upon its pivot without affecting any of the other arms.

It will be seen that by my invention garments may be compactly and in the most orderly manner supported in their closets 85 and the space most advantageously utilized, and yet when a particular garment is desired it can be brought to a position where without disturbance of any of the other garments and by the employment of both hands 90 it may most conveniently and comfortably be removed and the operation of returning or replacing it can be easily and comfortably performed, and this without the annoying twisting around upon an approximately vertical axis which occurs on ordinary hook-hung hangers. 95

Having thus described my invention what I claim is—

1. A garment hanger, comprising a side 100 by side series of garment-engaging members having a form to receive and support a garment, a movable arm for each of said members shiftable to project its said member from a position alongside its neighbor to 105 one beyond it to afford convenient access to said garment supporting member for applying or removing a garment, a pivotal connection between each member and its arm, whereby in all positions of said arm said 110 member remains in proper garment-supporting position, a common support for the arms on which each arm has an independent to and fro movement, which movement is in a plane perpendicular to the support, and means to hold said arm in the various positions to which it is movable. 115

2. A garment hanger, comprising a horizontally extending shaft, a series of arms mounted on said shaft to swing to and fro thereon, means to limit the swing of said arms through an arc less than a circle, a garment-engaging member proper having a form to receive and support a garment pivotally suspended from each of said arms so that it remains in garment-supporting position at all points of the swinging of the arm, and means to hold each arm in the various positions to which it is movable. 125

3. A garment hanger comprising a series 130

of garment-engaging members proper, arms suspending said members to swing on horizontal axes, a support for said arms upon which they are placed side by side and upon which they are movable to shift the position of the garment-carrying members proper in a vertical plane and independently of each other, friction devices for said arms, and a common adjusting means for

10 said devices.

4. A garment hanger, comprising a garment-supporting member proper, an arm

suspending said member to swing on a horizontal axis, said arm also being pivoted on a horizontal axis, a pivotal support for said arm, friction disks between which the arm is mounted, and means to prevent the turning of said friction disks.

In testimony that I claim the foregoing I have hereunto set my hand.

OBERLIN SMITH.
